(57) **CLAIM**

The ornamental design for a swiveling exercise weight as shown and described.

DESCRIPTION

FIG. 1 is a top perspective view of the swiveling exercise weight embodied in the present invention;

FIG. 2 is an end view of the swiveling exercise weight from FIG. 1;

FIG. 3 is a front view of the swiveling exercise weight from FIG. 1;

FIG. 4 is a top view of the swiveling exercise weight from FIG. 1; and,

FIG. 5 is a bottom view of the swiveling exercise weight of FIG. 1.

The dash-dash-dash broken line shown in FIG. 1-FIG. 5 is included for the purpose of illustrating the indefinite length of the horizontal bar and forms no part of the claimed design.
